APPARATUS FOR ROLLING FLANGES ON
TUBESEarle F. Lohmann, Overland, Mo., assignor to
Curtiss-Wright Corporation, a corporation of
Delaware

Application July 20, 1944, Serial No. 545,838

4 Claims. (Cl. 153—81)

1

This invention relates to a method of and apparatus for forming and working metallic bodies and is particularly directed to improvements in the forming of tubular bodies and the like.

The working of metallic bodies when reduced to a plastic condition is generally well known as evidenced by the highly developed art of forging solid bodies or bodies having thick wall sections. The hot or cold working of metals by the application of rotary or spinning methods is also an old and highly developed art and is especially applicable to the group of relatively ductile metals such as copper, aluminum, silver, gold, etc. For the group of relatively less ductile metals such as iron, steel, alloys of steel, etc., the prior forming methods in themselves are entirely inadequate particularly when applied to relatively thin walled metallic bodies. I have discovered that by a combination of spinning and press-forging it is possible to work the tubular metallic bodies of the less ductile group into desired forms and shapes. My method broadly consists in elevating the temperature of the body to be formed until it has attained a plastic state and then to follow this step immediately by a series of press-forging operations. It is also my intention to rotate or spin the body during the heating and forming steps so that the metal shall be evenly worked thereby producing uniform results with a high standard of perfection.

I am able to accomplish these results with the apparatus hereinafter to be described but which broadly consists of means for holding and spinning the tubular body to be formed and means consisting of a group of associated and freely rotatable backing and forming rolls. The backing rolls provide the means for supporting the body during the forming stages and for controlling the extent of body deformation. A series of cooperating forming rolls then are moved into the body and accomplish the press-forging steps so that the body may be made to conform to any desired shape.

The principles of my discovery have many applications but for present purposes of discussion as to its use and advantages the following description of the method and apparatus shall be specific to the treatment of tubular metallic bodies whereby a flange formation results. The flanged tubes formed according to this invention are much superior to the more common welded or riveted built-up flanged constructions for the reason that the flange is an integral and homogeneous part of the parent body metal.

One object of the present method is the at-

2

tainment of uniform results in the manufacture of tubular flanged bodies with consequent economy and high productivity.

It is also an object to provide a method for working tubular or hollow bodies by a combination spinning and press-forging operation once the body mass has been reduced to a plastic condition whereby the finished article possesses the most desirable physical characteristics and homogeneous structure throughout.

An object is to provide apparatus which shall carry into effect the method of spin-forging of tubular metallic bodies when said bodies have been first reduced to a plastic condition, the apparatus including means for rotating the tubular body together with suitable forming agencies which cooperatively act upon the body and force it into a configuration of the desired form.

Still another object is to provide a machine of a semi-automatic type and one by which the method of forming metallic bodies may be performed rapidly and simply.

These and other objects will become evident in the course of the following description relating to one embodiment of the invention and when considered in view of the accompanying drawings, in which:

Fig. 1 illustrates schematically in plan view the successive stages in the formation of a flange on the tubular body; the step (A) being the phase following the heating stage but just prior to the first action of turning the tubular wall by a conical breaking roll; step (B) being the initial breaking action to direct the tube wall mass into a flared formation; step (C) being the stage of complete tube wall flaring and turning; step (D) being the phase in which the turning roll means is moved away and a flat face finishing roll moved into operative position; and step (E) being the final phase of press-forging the flared and curled tube mass into a flat faced flange projecting at right angles to the tube axis.

Fig. 2 is a plan view of the apparatus herein preferred for carrying out the several steps of flanging or spin-forging a tubular body as shown schematically in Fig. 1, certain operating elements of the apparatus being omitted in this view.

Fig. 3 is a longitudinal elevation partly in section of the apparatus illustrating further features thereof.

Fig. 4 is an enlarged sectional elevational detail of the tube receiving spindle and rotating head of the tube forming apparatus.

Fig. 5 is an enlarged perspective detail of the

tube clamping and rotating chuck adapted to be secured to the right-hand end portion of the spindle means of Fig. 4.

Fig. 6 is also an enlarged perspective detail of the preferred tube centering or tube locating means normally positioned at the left-hand end of the spindle as seen in Fig. 4.

Fig. 7 is an end elevated view, partly in section, of the tube forming means and supporting carriage as seen along line 7-7 in Fig. 2.

Fig. 8 is an enlarged and partly broken and exploded perspective view of the forming means and carriage as viewed opposite to that in Fig. 7, and

Fig. 9 is a fragmentary elevational view of the heating means and tube supporting rolls with special attention directed to the means for timing the movement thereof in the tube heating and tube forming cycle of operations.

In the drawings and particularly Fig. 1 there is illustrated in progressive stage of flange formation a tubular body 10 which may be selected from a group of metals and alloys found desirable or suitable for the purpose in view. According to the preferred method of treating tubular bodies, the tube section 10 (Fig. 1,A) is centered and clamped in a rotating type chuck 11 with a suitable length of stock projecting from the face of the chuck to present just sufficient material for forming, the remainder of the tube being retained in and behind the spindle ready for subsequent operations as will appear hereinafter. The portion of the tubular body 10 to be formed is first heated until the desired plastic condition is reached, which for 4130 steel is about 1400 degrees F. or a light cherry red. The temperature to be attained for sufficient plasticity will of course vary with change of the material being formed. A uniform heat is reached by rotating the tube and chuck and at the proper time the heating means is removed and a back-
10 ing or supporting roll means 12 is brought into position adjacent and tangent to the tube circle but rearwardly of the tube end as shown. This supporting roll 12 is freely rotatably mounted on an adjustable carriage 13 with its axis of rotation normal to that of the tube. Immediately following the positioning of the roll 12 a conically shaped breaking roll 14 is moved axially into the tube where it assumes a position with its conic face parallel to and in rolling contact with the inside surface of the tube wall at a point which is opposite the point of contact of the supporting roll 12 with the tube exterior. This spaced relationship of rolls 12 and 14 will vary with changes in the tube wall thickness and therefore, the conical roll 14 is carried in an adjustable mounting means 15. Roll 14 is pressed into the tube until the angularly related conical face contacts the inner peripheral margin of the tube and causes the tube wall to break or expand outwardly, as indicated at 16 in Fig. 1,B, into a flared formation. The tube rotation will cause this flared formation to assume uniform proportions over the tube circumference.

While the tube mouth is being radially expanded or flared by continual inward movement of the conical roll 14, a turning roll 17 is brought up by the same means utilized for advancing the conical roll and contact between the tube flare 16 and the curved face 18 of the turning roll is established. The roll 17 is freely rotatable on an axis normal to the tube axis and is also in a position closely adjacent the roll 14 along a tangency line corresponding to a projection of

the contacting tangency line between the cone roll and tube. The action of this turning roll 17 is clearly indicated in Fig. 1,B where it picks up the tube flare 16 and continues or accelerates the radial expansion, and in Fig. 1,E where it acts to crowd the tube flared portion 16 back on itself in a sharply curled formation until the flare approaches the backing roll 12. Further increase in the diameter of the flare 16 is prevented by the positioning of a flange controlling, blade type roll 19 with its axis of free rotation normal to that of the roll 12 and substantially parallel with the axis of the tubular body 10. The blade roll 19 is arranged to overlap the roll 12 an amount sufficient to prevent the tube flare from extending beyond the width of the roll 12 and to act as the means for controlling and restricting the width of the flange formation.

The final stages of the method involve the substitution for the turning roll 17 of a flat finishing roll 20. This is accomplished (Fig. 1,D) by retracting the rolls 14 and 17 and indexing the flat roll 20 into its operative position and the turning roll 17 out of position. The roll changing and indexing means is shown generally at 21 and is actuated manually in this arrangement to swing the roll 17 downwardly and to the rear where it becomes inoperative and to swing the roll 20 downwardly and forwardly where it occupies the position formerly assumed by roll 17. When this change has been effected, the roll organization is again fed into the flange 16 (Fig. 1,E) and the final flange forming phase performed. In this latter phase the flat roll 20 presses or forces the reversely turned flare 16 against the back roll 12 flattening it out and at the same time forcing the metal to flow outwardly against the control blade roll 19 and inwardly against the conical roll 14 thereby resulting in squared-up outer and inner flange margins. At the same time the tube wall thickness is maintained by the relationship of rolls 12 and 14 so that there occurs no reduction in thickness of material at any zone of the tubular wall. The flange thickness is determined by the extent of inward travel of the flat roll 20 and by the metal flow in a radial direction permitted by the control roll 19.

One form and arrangement of apparatus by which the presently preferred method may be carried out is disclosed in the several remaining views of the drawings and for a general understanding thereof reference will be had to Figs. 2 and 3. The apparatus comprises a base member 22 in the form of a rigid I beam with the web portion 24 horizontally positioned and supported through the flanges 25 and 26 together with bolster members 27 positioned at the upper end of the legs 28, the latter being suitably braced and strengthened by members 29 and 30. The table-like web 24 supports near the left end a rotary spindle organization 31, which is comprised of a central structure 32, partly enclosed by a cover 33, and at the forward and rear ends respectively a chuck member 11 and a work centering mechanism 35. A portion of the sheet metal cover 33 for the structure 32 has been broken away to reveal the spindle driving pulley 36 which is connected through a plurality of V-belts 37 to the drive pulley 38 of a hydraulic speed control unit 39 which, in turn, receives its power from a gear connected electric motor 40. The latter hydraulic unit and motor is carried on a base plate 41 pivotally mounted on a shaft 42 at one side (Fig. 2) and resiliently supported by a rod

43 and spring 44 at the front side. A plurality of floor legs 45 and associated brace struts 46 support the shaft 42 as shown.

The details of the spindle organization (Fig. 4) include a cast base structure 32 in which supporting and axial thrust bearings 50 are carried for the rotary hollow or tubular spindle 51. The external face of the spindle 51 is formed to provide circumferentially machined surfaces for the inner races of the bearings 50 and also for the keyed securing of the V-belt pulley 36 intermediate the length of the spindle and between the upstanding portions of the structure 32. An adapter flange member 52 welded or otherwise secured to the right hand end portion of the spindle 51 acts as an abutment for the adjacent thrust bearing 50 and also as the means for locating the spindle in operative position. A retainer ring element 53 is threaded on the spindle at the left hand portion thereof and through the interposition of a spacer ring or collar 54 serves to confine the assembly from axial displacement. The pulley 36 located on the spindle 51 is enclosed by the sheet metal cover 33 attached directly to the structure 32 and confined between flanges 55. As indicated (Fig. 3) the spindle housing structure 32 is bolted as at 56 directly on the table 24 between the front and rear side flanges of the principal supporting structure 23.

The chuck type tube clamp and rotating member 11, suitably bolted as at 60 to the adapter flange 52 carried by the spindle 51, is shown in Fig. 5 as comprising a base member 61 having a central aperture 62 of substantially the same diameter as the internal diameter of the spindle. The face 63 of this member 61 carries a first set of pivot-forming blocks 64 for the pivotal support of an alignment plate 65 and a second set of similar blocks 66 for pivotally mounting a second alignment plate 67, the two plates cooperating when in closed position to bring the tubular work piece into a vertically centered position (as viewed in the drawing) with respect to the axis of rotation of the chuck. The centering plate 67 is shown in its full open position while the plate 65 is shown fully closed. Each of these plates is provided with a semi-circular recess 68 of a size slightly larger than the outside diameter of the tubular body to be held in the chuck. Obviously a change in tube diameter will make it necessary to replace these centering plates with an appropriate set having recesses 68 sufficiently larger or smaller to receive the tubular body. In addition to these centering plates 65 and 67 the chuck face 63 carries a yoke member 70 which is made up of side elements 71 secured at their upper ends to a cross block 72, and at their lower ends on pivot forming pins 73, the latter being integral with a yoke supporting slide block 74. The yoke may be pivoted outwardly and down as viewed in the drawing, but in its operative position is arranged to lie between and in a plane behind the pivoted centering plates 65 and 67 as indicated. The slide block support 74 is secured to the chuck through a pair of gib or dovetail guides 75 which receive therebetween a matching dove-tail projection (not shown) formed on the rearward face of the slide so that it may be adjustably positioned in a radial direction across the chuck face and within the limits defined by a slotted recess 76. A pin (not shown) carried in the rear face of the slide block dove-tail piece projects into the slot 76 where it acts to limit the radial travel of this member.

The tube clamping or securing means comprises a pair of gripping blocks 77 and 78 slidably positioned between the yoke side pieces 71. The block 77 is secured to the yoke supporting block 74 and consequently may be positionally adjusted therewith. The cooperating block 78 is secured to a crosshead member 79, which, in turn, is slidably attached to the chuck face by the provision of gib blocks 80 which receive a dove-tail projection (not shown) integrally formed on the rear face of the crosshead 79. In this manner the crosshead 79 and gripping block 78 may be adjustably positioned independently of the yoke means in a radial direction toward or away from the associated grip block 77 and yoke support 74. It will be noted that each of the gripping blocks is formed with a semi-circular recess 81, which, when the blocks are placed in adjacency, provides a circular aperture of a size sufficient to engage the tubular body and hold the same in position. For changes in the dimensions of the body to be held thereby, the gripping blocks 77 and 78 are arranged to be removable so that a similar set of blocks, each having a suitably enlarged or smaller recess 81, may be substituted. A clamping screw element 82 threaded through the yoke head block 72 presses against the upper end surface of the crosshead 79 thereby forcing the gripping block 78 into contact with the tubular body positioned in the recess 81. At the same time, the reaction of screw element 82 on the upper block 79 is transmitted through the yoke 70 to the lower block 74 causing a concurrent upward movement thereof to bring each of the gripping blocks into engagement with the tubular body intended to be held within the recess 81.

In securing a body or tubular work piece, such as tube 10 in Fig. 1, in the chuck the centering plates 65 and 67 are pivoted to the open position, that is the position assumed by the plate 61 in the drawing, and screw 82 is backed off sufficiently to permit separation of the jaws 77 and 78. The body is then passed through the bore of spindle 51 and projects into and through jaw recesses 81 the desired amount. Thereafter jaws 77 and 78 are brought into gripping contact with the body by turning up the clamp screw 82 in yoke cross-head 72 and centering plates 65 and 67 are pivoted into closed position to center the body in a vertical position. At the time jaws 77 and 78 are moved into the body a locking piece or finger 83 on block 79 is positioned in adjacent notches 84 and 85 of the respective plates 65 and 67 thereby securing the centering plate means against unintended opening during the rotation of the chuck 11.

In Fig. 6 there is illustrated the details of a body locating and centralizing device 35 which is mounted at the rear end of the tubular spindle 51 in an adapter ring 86 (Fig. 4) secured to the spindle by one or more set screws 87. The device 35 comprises a base plate 88 preferably secured to the adapter ring 86 by means of three dowel pins 89 (only one being shown in Fig. 6) 65 which are slidably mounted in apertures 90 in the adapter for axial adjustments of the member 35. As shown in dotted outline in Figure 6, the single dowel pin 89 has a reduced end portion which is inserted in an aperture in the plate and is so held by a nut threaded thereon as at 89a. Of course the other dowels will be similarly secured to plate 88. A set screw 91 locks the dowel pin 89 in either one of two positions as defined by the set screw receiving recesses indicated 70 75 (dotted outline) in the dowel pin shank. A sec-

ond plate 92 coaxially positioned with the base plate 88 is mounted thereon for relative rotation whereby a plurality of finger elements 93 may be made to move into or out of the area defined by the body receiving apertures 94 and 95 in the base plate 88 and adjustable plate 92 respectively. Each finger element 93 is positioned between the plates 88 and 92 and is also pivoted about a stud bolt 96, the latter being anchored in base plate 88, and further being provided with an enlarged shouldered portion (not shown) intermediate its ends for the purpose of establishing a predetermined fixed spacing between the plates 88 and 92. It should be noted that the securing nuts, as at 89a, for the dowel pins 89, only one of which has been shown, are located in the space between the plates 88 and 92. The rotatably adjustable plate 92 is provided with circumferentially directed arcuate slots 97 to receive the bolts 96 and to permit a limited amount of angular shifting of plate 92 with respect to the base plate 88. A suitable nut 98 is threaded on the outer end of each bolt 96 and serves to secure the several parts from unintended displacement when tightened up. The means provided for rotating each finger element 93 and thus for adjusting the centering device to accommodate various tube sizes consists of a pin element 99 carried at the inner end of the finger and adapted to move in a pin guide slot 100 having a spiral trend as indicated. Depending upon the direction of rotation of the plate 92 it is possible to move the rear end of each finger element 93 so that the fingers may be spread out to lie flush with the inner circumference of the plate aperture—or, as shown, moved inwardly to a partially inwardly extended position. In order that plate 92 may be held against rotation as a consequence of the off-center force developed on plate 92 when nuts 98 are being drawn up or loosened there is provided a series of plate holding means (three being indicated) consisting of nut elements 101 welded to the face of plate 92 which may be engaged by a wrench or other tool for balancing the off-center force on the plate during the time a second tool is used to turn nuts 98. With the nuts 98 loosened, plate 92 may be rotated relative to plate 88 by hand.

The means and agencies utilized in performing the body shaping operations shown in great detail in Figs. 7 and 8 and in somewhat lesser particularity in Figs. 2 and 3 comprise a base plate 102 pivotally mounted on a back shaft 103 through spaced arms 104 and further supported and held against unintended displacement by a toothed rack element 105 engaged with a second toothed rack element 106 fixed to the main table surface 24 (Fig. 3). Back shaft 103 is supported in a plurality of suitable brackets 107 attached to the rear flange 25 of the table. The base plate 102 provides a slide way for a reciprocating carriage 108 in which a pair of gibbs 109 secured in the margins of the slide way receive a dove-tail piece 110, the latter being fixed on the bottom surface of the carriage 108 (Figs. 7 and 8). The carriage 108 is reciprocated in its slide way on base 102 by means of a piston rod 111 associated with a cylinder 112 (Figs. 2 and 3) which is secured to the table surface by means of a bracket structure 112a as shown. The rod 111 is releasably connected with the carriage 108 by means of a slotted block member 113 secured at the rear marginal portion of the carriage and engaging with a mating grooved cylindrical element 114 on piston rod 111. A further

discussion of the purpose and operation of this cylinder and carriage connection will appear presently.

The carriage 108 mounts at the forward and back zone thereof the set of forming rolls 17 and 20 respectively utilized in turning and finishing the tubular body flange formation. These rolls are freely rotatably mounted on an indexing head block 21, the latter being pivoted on an axially adjustable shaft 115, in turn, supported in a split type bearing block 116 secured to the carriage 108 in any suitable manner. The indexing head block 21 is provided with a handle 117 and a detent (not shown) which is adapted to engage in one of two roll positioning recesses (not shown) provided in the shaft 115. A lever member 118 pivoted on handle 117 operates the detent in a well known manner when the lever is moved toward handle 117. Also mounted on the carriage 108 substantially in front of the position of the rolls is a secondary carriage 119 slidably secured by means of a dove-tail projection 120 between a pair of gib elements 121 in turn secured to the primary carriage 108. The means for moving the carriage 119 in the slide way afforded by gib 121 is indicated at 122 and comprises a block fixed to carriage 108 and threadedly receiving a screw shaft which is rotatably secured to the carriage 119 in a well known manner. The upper face of secondary carriage 119 provides a mounting surface, defined by integral but spaced flanges 123 for guiding a block member 124 therebetween and in a direction normal to the travel of the secondary carriage. Block 124 is positionally adjusted toward or away from the rolls 17 and 20 by a block and threaded element 125 which is similar to the means 122 associated with the secondary carriage. In addition to the adjusting means 125, block 124 is provided with slotted apertures 126 for the reception of clamping bolts or the like 127 (Fig. 2), which bolts engage the secondary carriage 119 in threaded apertures 128 (Fig. 8). The adjustability of carriage 119 and block 124 is required so that the conical roll member 14 mounted in a skewed axis aperture 129 in block 124 by means of a shaft 130 integral with the roll 14 may be positioned internally of the tubular body to be formed as conditions of operation demand. The shaft 130 is freely rotatable in aperture 129 but is retained from axial displacement by a suitable set screw or other retaining means (not shown) inserted in aperture 131 and engaging an annular groove 132 in shaft 130.

The rolls 17, 20, and 14 cooperate in the manner before described in detail in connection with Figs. 1,A to 1,E. The adjustability of each of these rolls is obviously necessary so that flanging operations may be performed on a number of different size tubular bodies, one such tubular body being indicated at 16 in Fig. 7 with a flange formed thereon at 18. Thus the relative position of the forming rolls and body may be clearly observed and understood.

In addition to the above noted roll elements there is provided a backing or supporting roll member 12 freely rotatably mounted on an adjustable member 13 which is carried on a swinging arm 133, the latter arm pivoting about the back shaft 103 in the manner indicated in Figs. 7 and 9. The means for adjusting the position of roll 12 is indicated at 134 while an hydraulic unit 135 pivotally supported on depending bracket 136 has its operating rod 137 connected to a bell-crank or arm 138 integral with swinging arm 133.

The member 13 also carries a freely rotatable flange controlling blade-type roll 19, which roll maintains a fixed position relative to backing roll 12 for any given flange formation desired to be spun-forged from the tubular body 10 (Fig. 9). In the illustrated embodiment the blade-type roll 19 is mounted so that when in operative position it bears a fixed spaced relation to the tube axis, because in this embodiment it is not deemed necessary to move it outwardly or inwardly of the tube axis to vary the flange depth and flow of material in the peripheral zone of the flange, but obviously the roll may be adjustably mounted on its support if desired.

One of the preparatory steps to the formation of a body flange is the reduction of the body to a plastic state and in the present instance is achieved by means of an open flame heating organization shown in Figs. 3 and 9. The heating means comprises a plurality of torch heads 139 each carried on a bracket member 140 at the outer end of a beam element 141, the beams being pivotally mounted in a bracket 142 on spindle frame 32. A beam counterweight 143 facilitates the raising and lowering of the heating torches which are movable in unison due to the beam tie bar 144. The heating means is adapted to work in conjunction with the swinging arm 133 (Fig. 9) so that when the heating torches (dotted outline) are positioned to heat the body 10 the arm 133 and associated rolls move out of the way (dotted outline) and conversely when the body is sufficiently plastic the heating means can be removed quickly to the full line position and rolls 12 and 19 positioned for the forming operations. To accomplish this timing of the heating means and roll supporting arm there is provided an operating rod 145 having a swivel connection 146 with bracket member 147 on beam elements 141 and a pivotal connection with an extension of the pivot pin utilized to connect crank arm 138 with piston rod 137 (see Figs. 2 and 9).

The hydraulic units 112 for the carriage organization 102 and 135 for the swinging arm 133 and heating torch organization are supplied with fluid from a central control station 150 which, in turn, receives pressure fluid through conduit 151 from a pump 152 driven by a belt connected motor 153. The fluid is returned to the suction side of this pump by way of conduit 154. The fluid conduit system from the control station is incompletely shown so as not unduly to confuse the drawings, but it should be noted that any suitable fluid conduit system may be utilized. From the central control 150 (Fig. 2) a pair of dual supply and return conduits 155 and 156 conduct pressure fluid and exhaust fluid respectively to the appropriate and corresponding inlet and exhaust connections similarly indicated at the opposite end connections at the cylinder 112. Similarly conduits 157 and 158 lead from valve unit 159 to their opposite end connections shown at the cylinder 135 (Fig. 9) for supplying and returning exhaust fluid for that actuator means. A valve control lever 159 is provided for a double acting valve disposed in fluid lines 155 and 156, and likewise a second lever 160 operates a double acting valve associated with fluid lines 157 and 158.

The operation of the above described apparatus is as follows: The hydraulic unit 112 is initially positioned to hold the carriage 108 and associated parts in a retracted position, viz. in a position to the right as viewed from Fig. 3. This will en-

able the machine operator to pivot the carriage base plate 102 upwardly and back about its back shaft 103 upon release of a clamping type hold down element 161 located at the front of the base plate. This pivoting movement of the base plate is facilitated by the addition of a pair of counterweights 162 mounted at the rear of the arms 104. It is necessary to retract carriage 108 so that the piston rod 111 will be clear of the base member 102 and also to allow the members 113 and 114 free separating movement when breaking the operating connection therebetween.

With the above mechanism and parts pivoted to an out of the way position, the next operation is to feed the tubular body through the centering device 35, spindle 51 and chuck 11 by means of a friction type hitch plate 163 pivotally mounted on a rolling carriage 164 and adapted to be operated by a handle 165. The hitch carriage travels on track member 166 carried by the table structure 23 as shown in Figs. 2 and 3. By this means the tubular body is fed into the zone of the forming rolls the required distance and is thereafter secured in place by the chuck 11 in the manner already noted. Also the tube centering means 35 is adjusted to center and secure the work piece in a concentric relation with the hollow spindle 51. The spindle and tube may then be rotated by energizing the motor 40 and the desired speed of revolution adjusted by the hydraulic speed controller 38. At this time the member 102 is returned to operative position and connection between elements 113 and 114 reestablished. The heating means 139 are positioned in adjacency to the spinning body 10 by proper manipulation of valve lever 160 which controls hydraulic actuator 135 and heating takes place until the proper temperature for the required degree of plasticity is obtained in the mass of the body subject to the forming operations. Upon attainment of the proper heat, actuator unit 135 is energized through control valve 160 to move the backing roll 12 into operative position (full line in Fig. 9) while withdrawing the heating heads 139. Thereafter valve 159 is manipulated to advance the carriage 108 axially toward the heated tubular body by application of pressure fluid to cylinder inlet connection 156. At the time of first feeding the rolls into the tube end the turning roll 17 occupies the advanced position of roll 20 as shown in Fig. 8. The tube is accordingly spun into a flared and curled formation by the co-action of conic roll 14 and turning roll 17 in the manner described before. Upon completion of this step, cylinder unit 112 is operated reversely to retract the carriage unit 108 sufficiently to enable the manual change of position of rolls 17 and 20 through the indexing head means 21 whereby roll 20 is the more advanced. Again the carriage organization is advanced toward the partially formed tubular body and a completed flange is press-forged by the co-action of the conic roll 14 and flat or forge finishing roll 20, these being arrested by flange controlling blade type roll 19 and backing roll 12.

After the flange is completely formed on the tubular body 10, by the combined spinning and press-forging operations now described, the carriage supporting base 102 is pivoted out of the way as previously noted and an adjustable stop means 167 is moved along the front flange 26 of the supporting table 23 and secured at the proper point thereon so that the required length of tube may be measured off prior to advancing a standard type of lathe cut-off tool 168 into

11

the side of the tube. The cut-off step is effected while the tube is rotated by the chuck it as is well understood.

The method above described together with apparatus for the practice thereof has been directed to a specific application for the production of flanged bushings or other parts from tubular stock. It should be recognized that there are other forms and shapes which may be made by applying the same principles to apparatus of modified form coming within the scope of the appended claims.

What is claimed is:

1. Apparatus for flanging a tubular body including a frame having means thereon for supporting said body for rotation, motor means on said frame for rotating said body supporting means, carriage means operatively disposed on said frame for movement toward or away from said body, power means on said frame for moving said carriage, a first set of flange forming rolls operatively mounted on said carriage in position to contact said body and radially expand the same for forming a flange thereon by movement axially into the body upon movement of said carriage toward said body, a second set of flange forming limit rolls, a support for said latter rolls carried on said frame for pivotal movement into and out of a position in which they are disposed in fixed relation with respect to said body and said first set of rolls, heating means pivotally mounted on said frame for movement into and out of a position adjacent the body to heat the latter, means operatively interconnecting said pivotal support and said heating means for timing the pivoting movement thereof such that as said heating means pivots into or out of its said position, said pivotal support will pivot respectively out of or into its said position, and means on said frame connected to said pivotal support for moving the same.

2. Tube flanging apparatus comprising means for supporting and rotating a tube, a carriage movable axially of the tube, a flaring roll mounted on the carriage with its axis inclined to the tube axis, said flaring roll having a substantially conical face which on one side thereof is engageable tangentially along the inner surface of the tube for supporting the latter against inward deformation and on the opposite side thereof is inclined relative to the inner surface of the tube for flaring the end of the tube upon axial movement of the carriage, a pair of flange forming rolls mounted on the carriage in a manner to be brought alternately into engagement with the flared portion of the tube, each of said flange forming rolls when in the tube engaging position thereof having its axis of rotation substantially normal to the tube axis, one of the flange forming rolls being so shaped in profile as to curl the flared portion of the tube upon axial movement of the carriage, a backing roll rotatable on an axis substantially normal to the tube axis for cooperating with the other of the flange forming rolls to roll the curled portion of the tube therebetween, and a limit roll rotatable on an axis substantially parallel to the tube axis for engaging and limit-

12

ing radial expansion of the tube flange formed between the backing roll and said other of the flange forming rolls.

3. Tube flanging apparatus comprising means for supporting and rotating a tube, a carriage movable axially of the tube, a flaring roll mounted on the carriage with its axis inclined to the tube axis, said flaring roll having a substantially conical face which on one side thereof is engageable with the tube tangentially along the inner surface thereof for supporting the latter against inward deformation and on the opposite side thereof is inclined relative to the inner surface of the tube for flaring the end of the tube upon axial movement of the carriage, a pair of flange forming rolls mounted on the carriage in a manner to be brought alternately into engagement with the flared portion of the tube, each of said flange forming rolls when in the tube engaging position thereof having its axis of rotation substantially normal to the tube axis, one of said flange forming rolls being so shaped in profile as to curl the flared portion of the tube upon axial movement of the carriage, and a backing roll rotatable on an axis substantially normal to the tube axis for cooperating with the other of said flange forming rolls to roll the flared portion of the tube therebetween.

4. Tube flanging apparatus comprising means for supporting and rotating a tube, a carriage movable axially of the tube, a flaring roll mounted on the carriage with its axis inclined to the tube axis, said flaring roll having a substantially conical face which on one side thereof is engageable tangentially along the inner surface of the tube and on the opposite side thereof is inclined relative to the inner surface of the tube for flaring the latter upon axial movement of the carriage, a flange forming roll mounted on the carriage for rotation upon an axis substantially normal to the tube axis, and a backing roll rotatable on an axis substantially normal to the tube axis for cooperating with said flange forming roll to roll the flared portion of the tube therebetween.

EARLE F. LOHMANN.
